GLOVE LINING

William H. Kuh, Marinette, Wis., assignor to
Eisendrath Glove Company, Chicago, Ill., a
corporation of Illinois

Application April 7, 1937, Serial No. 135,568

2 Claims. (Cl. 2—164)

The invention relates to gloves and has as an object the provision of a glove having the warmth characteristics of a fur-lined glove but eliminating objectionable features thereof.

It is a further object of the invention to provide a glove that will offer all the advantages of a fur-lined glove but is economical to produce and superior in use to a fur-lined glove.

Further objects of the invention will appear from the following description when read in connection with the accompanying drawings showing an illustrative embodiment of the invention, and wherein:

Figure 1 is an elevation from the palm side;

Figs. 2 and 3 are transverse sections on lines 2—2 and 3—3 respectively of Figure 1;

Fig. 4 is an elevation of the lining for the back;

Fig. 5 is a plan view of a thumb blank for a lining;

Fig. 6 is an elevation of the palm lining with the thumb lining and the wrist lining omitted;

Fig. 7 is a perspective view of a wrist lining blank;

Fig. 8 is an elevation of the palm side of the complete lining; and

Fig. 9 is an elevation of the palm side of the glove blank.

As shown the device comprises a glove blank 30 or outer portion 10 and a lining made up of a back portion 11 of fur and a front portion 12 of absorbent fabric. The lining of the glove is completed by means of a thumb blank 13 and a wrist lining 14, the thumb portion being preferably formed of the same material as that of portion 12, and the wrist lining of the same material as portion 11.

In the making up of the lining the thumb lining is closed and sewn into the opening 13' in the usual manner and the members 11 and 12 are sewn together along the index finger side 24 throughout. The little finger side is then sewn as shown at 15, Figure 8, to a point 16 approximately at the juncture of the finger blank 13 with the palm blank. The parts 11 and 12 are also united by stitching around the tips of the fingers, as indicated at 17, 18, 19, 20, leaving the side edges of the finger blanks of the palm and back disconnected with the exception of the in-

dex finger edge. The wrist lining 14 which is desirably of fur is then attached by stitching 21 after which the assembled lining is drawn into the glove blank 10 and secured thereto by the binding and hemming at 22, 23.

A fur-lined glove is objectionable to many persons because the fur and pelt are relatively non-absorbent and the hands as a whole are often kept too warm, causing the palms to perspire. This perspiration is not absorbed, causing discomfort to the wearer. In the glove of the present invention the palm portion of the lining is made of absorbent material, which incidentally is fabric and longer wearing than is the usual fur of a fur-lined glove. The glove therefore actually wears longer and is more comfortable although cheaper to produce. The fur which is objectionable from the non-absorbent standpoint is not necessary for warmth in the palm side of the lining.

Further, the glove of the present invention is less bulky when objects are grasped by the hand encased therein as the absorbent fabric of the lining is less bulky than is fur. This fact makes the glove very fine for use as a driving glove, giving ample protection to the back of the hand and yet allowing a firm grasp of the steering wheel.

Minor changes may be made in the physical embodiment of the invention within the scope 30 of the appended claims without departing from the spirit thereof.

I claim:

1. A glove lining comprising, in combination: a fur back lining portion with the hair side inward; an absorbent fabric palm lining portion; rows of stitching joining only the registering edges of said lining portions at the index finger edge, about the finger tip edges and through the little finger edge of the palm and back portion.

2. A lined glove comprising, in combination; an outer glove body; a lining enclosed in said body and secured thereto only at the wrist; said lining comprising a back of fur with the hair turned inwardly and a palmar side of fabric; the inter-digital edges of said back and palm lining being disconnected.

WILLIAM H. KUH.
